UNITED STATES PATENT OFFICE.

JAMES LESTER MAUTHE, OF ELYRIA, OHIO.

SPLASHER PLATE FOR BLAST FURNACES.

Application filed February 9, 1927. Serial No. 166,898.

This invention relates to splasher plates for blast furnaces and more particularly to a novel mounting and operating mechanism for such plates, and has for one of its objects the provision of power means for moving the splasher plate into and out of position.

Another object is to provide a plate mounting which will maintain the plate on the furnace at all times, thereby preventing the danger of the plate being dropped while being manipulated into position and endangering workmen.

A further object is to provide a splasher plate and operating mechanism having the novel design, construction and combination of parts hereinafter described and illustrated in the accompanying drawings.

In the drawings—

20 Figure 1 is a front elevation of a portion of a blast furnace having my invention applied thereto.

Figure 2 is a plan view showing my invention applied to a blast furnace.

25 Figure 3 is a partial side elevation of a blast furnace showing the splasher plate and iron runner in section.

Referring more particularly to the drawings, the numeral 2 designates the bosh wall 30 of a standard blast furnace, the upper portion or stack (not shown), of which is supported on the furnace columns 3. The furnace is provided with the usual iron tapping hole 4, and in front of the tapping hole is a skimmer trough or runner 6, in which molten metal is conducted from the blast furnace to the skimmer, from which it flows into the iron runners leading from the discharge end of the skimmer to the pouring 40 spouts or, when used, to the pig beds.

The metal when tapped into the trough or runner 6 splashes and presents a turbulent flow, so that it is the practice to place a splash plate 8 over the furnace end of the trough 6 to prevent the metal splashing over the sides of the trough. Heretofore the splash plates 8 have been separate from the furnace and have been manually lifted onto and from the trough.

50 The splash plate 8 of the present invention is suspended from a rock shaft 9 journaled in bearings 10 secured on the furnace shell. The plate 8 has a pair of short angles 12 secured to its upper face to form supporting lugs which are apertured to receive a pivot bolt 13. A pair of suspension levers 14 are

keyed to the shaft 9 and have their lower ends apertured to receive the bolt 13, the bolt 13 forming a pivotal connection between the levers 14 and angle lugs 12.

55 A power lever 15 is keyed to the shaft 9 and has its free end connected by a clevice 16 to a short length of chain 17, which in turn is connected to one end of a cable 18, which is trained over suitable sheaves 19 and 60 has its other end connected to the piston rod 20 of a fluid pressure cylinder 21, which may be mounted on any suitable base such as the cast house column 22, as shown.

65 The splash plate 8 is shown in its lowered or operative position in the drawings, and when it is desired to move the plate into inoperative position, it is only necessary to admit fluid under pressure to the cylinder 21 which will cause the piston rod 20 to move into the cylinder and thereby pull on the cable 18 to raise the power lever 15. When the lever 15 is raised the shaft 9 will be rocked to raise the levers 14 and splash plate 8.

70 When it is desired to move the splasher plate 8 into operative position, the operation of the cylinder 21 will be reversed so as to permit the plate 8 to be lowered into operative position by gravity.

75 It will be readily understood that manual labor in handling the splasher plate 8 of this invention is entirely dispensed with, thereby facilitating the use of the plate and giving safety to the workmen.

80 While I have shown and described one specific embodiment of my invention, it will be understood that I do not wish to be limited thereto since various modifications may be made without departing from the scope 85 of my invention as defined in the appended claims.

I claim—

1. The combination with a blast furnace, having the usual tapping hole and runner trough, of a splash plate pivotally supported on said furnace for vertical movement and adapted to be raised and lowered into and out of position over said trough adjacent the tapping hole, and power means 100 for raising and lowering said splasher plate.

2. The combination with a blast furnace, having the usual tapping hole and runner trough, of a splash plate, a shaft journaled on said furnace, means for rotating said shaft, and means connecting said splasher plate and said shaft whereby said plate may 105

be raised and lowered by rotation of said shaft.

3. The combination with a blast furnace, having the usual tapping hole and runner trough, of a shaft journaled on said furnace, a splasher plate secured to said shaft and adapted to be moved vertically into and out of position over said trough by the rotation of said shaft, and power means for rotating 40 said shaft.

4. The combination with a blast furnace, having the usual tapping hole and runner trough, of a shaft journaled on said furnace, a splasher plate secured to said shaft and adapted to be moved vertically into and out of position over said trough by the rotation 45 of said shaft, a lever secured to said shaft, a source of power, and a connecting element connecting said source of power and said lever for causing rotation of said shaft.

5. The combination with a blast furnace, having the usual tapping hole and runner trough, of a shaft journaled on said furnace, a splasher plate secured to said shaft and adapted to be moved vertically into and out 55 of position over said trough by the rotation of said shaft, a lever secured to said shaft, a source of power, and a flexible connecting element connecting said source of power and said lever for causing rotation of said shaft.

6. The combination with a blast furnace, having the usual tapping hole and runner trough, of a shaft journaled on said furnace, a splasher plate secured to said shaft and 60 adapted to be moved vertically into and out

of position over said trough by the rotation of said shaft, a lever secured to said shaft, a fluid pressure cylinder, and a connecting element connecting said cylinder and said lever for causing rotation of said shaft. 40

7. The combination with a blast furnace, having the usual tapping hole and runner trough, of a shaft journaled on said furnace, a splasher plate adapted to be moved vertically into and out of position over said 45 trough, means connecting said plate and said shaft whereby said plate will be raised and lowered by rotation of said shaft, a lever secured to said shaft, a fluid pressure cylinder, and a connecting element connecting 50 said fluid pressure cylinder and said lever.

8. The combination with a blast furnace, having the usual tapping hole and runner trough, of a shaft journaled on said furnace, a splasher plate adapted to be moved vertically into and out of position over said trough, levers pivotally connected to said splasher plate and keyed to said shaft whereby said plate will be raised and lowered by 55 rotation of said shaft, a second lever keyed to said shaft, a fluid pressure cylinder, and a flexible connecting member connecting said cylinder and said last named lever, whereby operation of said fluid pressure cylinder will rock said last named lever and rotate said 60 shaft.

In witness whereof, I have hereunto signed my name.

JAMES LESTER MAUTHE.
